VENDING MACHINE

Parker H. French, Somerville, Mass., assignor to
Trimount Coin Machine Company, Boston,
Mass.

Application June 12, 1936, Serial No. 84,917

3 Claims. (Cl. 221—108)

The present invention relates to a vending machine, and more particularly to a vending machine in which goods are vended in bulk, particularly sweets, nuts, gum or the like, and in fact any other merchandise of small size that may be advantageously vended through a vending machine.

The art of vending machines has been substantially developed within recent years, both in respect to vending of package goods and also of goods sold in bulk, yet as in many such arts, continued developments are both necessary and welcome to the trade for the purpose of providing vending machines which will operate more easily, more uniformly and more reliably at a minimum cost of the machine itself.

The present invention in this respect provides an efficiently operated vending machine in which in particular bulk vending is possible in a reliable manner. It is possible in the present invention to adjust easily the amount of goods to be given to the purchaser with each purchase, and to be assured that a full measure is uniformly presented at each sale.

In addition to this, the present invention provides a means whereby bulk goods cannot interfere with the mechanism of operation and thereby finally clog the machine so that it will not operate, and further provides special means to safeguard against the use of slugs or the like instead of the proper coins to operate the machine. In addition to this the machine also provides for the reception of a number of coins in case more than one measure is desired, that is, the purchaser may put in two, three coins, or more and then turn the handle or lever the desired number of times to take out the correct number of measures corresponding to the coins inserted.

Further and additional improvements will be pointed out in the description of the embodiment containing the invention as set forth in the specification in connection with the drawings, in which:

Figure 1 shows a fragmentary sectional view through the machine looking from the back towards the front of the machine.

Figure 2 shows a fragmentary section of a part of the machine looking from the back as viewed in Figure 1.

Figure 3 shows a section on the line 3—3 of Figure 1.

Figure 4 shows a fragmentary section looking from the end as set up in Figure 1, of the machine with part of the casing removed.

Figure 5 shows a plan view of some of the mechanism shown in Figure 4.

The device as indicated according to Figure 1 may be provided with a number of compartments 1, 2 and 3, formed by the sides 4 and 5 and partitions 6 and 7. The compartments may be made

visible by the glass fronts 8, 8, 8, which are slidably positioned in channels formed by angles as indicated by the elements 10, 10, 10, etc. The back of the compartment is preferably extended straight downward, while the front is provided with lower partitions or walls 12, 12, 12, which slope downwards towards the rear as indicated more clearly in Figure 3. The elements shown in Figure 1 are preferably suitably positioned in a casing which covers the top of the containers 10 and the lower front allowing the glass 8, 8, 8, to serve as windows through which the merchandise in the compartments may be seen.

The inclined partitions 12, as indicated in Figure 3 may be attached by an angle support 13 to the side elements or partitions by bolts or rivets as indicated at 14 or in any suitable fashion. At the lower end of the compartment there is provided a floor or base 15 which has a circular opening 16, which is positioned symmetrically with a diameter containing the wall 17 extending vertically upward and the gates 18 and 19, 19 etc. These are indicated both in Figures 1 and 2 and also in part in Figure 3. The gates 18 and 19, 19 etc., are mounted to move or swing upon the shaft 20 which is supported by bearing brackets 21, 21, 21, 21, attached to the inclined floor 12. The gate 18 occupies approximately $\frac{1}{3}$ of the diameter, although it may be made larger or smaller dependent upon the size of the chamber that passes beneath it which contains the vended article, as will be explained below.

As viewed in Figure 2, the gate 18 is tensioned by means of the spring 22 bearing at one end against the wall 12 and on the other end against the inside of the gate 18, as viewed in Figure 2, in which part of the gate is broken away to indicate the spring. The gate, therefore as viewed in Figure 2 cannot move outward from the plane of the paper but may be moved inward by pressure against the lowered end of the gate which pressure, when released allows the gate to snap back into position. The set of gates 19 indicated at the right of Figure 2 operate in the opposite direction. These gates as indicated in the figure are seven in number and are formed in the shape of channels each with a spring having one end working in the channel and the other end tensioned against the inclined wall 12. These gates are so held by the position of their pivots 23 as indicated in Figure 2, so that they swing outwardly from the plane of the paper as shown in Figure 2, and snap back into position by the action of the spring.

On the outer half of the circular opening as indicated in Figure 3, there is mounted a lever 24 in the general shape of a bell-crank lever which is supported by a pivot 25 to a bracket 26 attached to the floor at the side of the opening. This lever normally swings downward, except 60

when the chamber beneath is filled with merchandise, in which case the merchandise lies beneath the lever which tends to break up any lumpiness or dislodge particles that may be present, as for instance, in candies or the like, where pieces may stick together. A more complete view of the operating mechanism is presented on an enlarged scale in Figure 4 and Figure 5, in which are shown a lower container or chamber 10 into which the merchandise from the upper compartments 8, 8, 8, are disposed before final delivery to the customer. Above the lower base or frame 15, there is mounted a cylinder or drum 26, which is composed of two main parts, an inner core element 27 and an outer shell element 28, Figure 5. The inner core element is provided with a number of recesses 29, 29, 29, 29, symmetrically placed about a center. The outer shell 28 has somewhat similarly positioned openings on the top face of the shell as indicated by 30, 30, etc. The outer shell covers the inner core and is adjustable with reference to it. This adjustment is obtained by means of the slots 31, 31, and the screws 32, 32, which are screwed into 25 the core through the slots holding the shell and the core in a fixed position one with the other when the proper positioning of the two elements is obtained. As indicated perhaps more clearly in Figure 5, the recess 29 extends in each case 30 under the outer shell as indicated by the dotted line so that by rotating the shell clockwise as indicated in Figure 5, the large opening or recess will be exposed. The outer shell is provided with downwardly extending apron 33 extending into the recess so as to close off the rest of the core 35 when this space is not desired as indicated by the dotted line. Graduations 34 at the side of the slot may be provided to indicate what size chamber should be used. The core and outer shell both operate together and are rigidly held 40 together after the proper adjustment is made. This system then rotates about the shaft 35 extending upward through the base 25. The outer shell is provided with a waving flange 29 and also projecting rotatable bars or rods 39 45 which serve the purpose as spur gears meshing with the spur gear 37 vertically positioned as indicated in both Figures 4 and 5. The flange 200 meshes with the tree 201 which rides on it and bobs up and down in the merchandise to 50 keep it broken up. The gear 37 is mounted directly upon the shaft 38 to which the outer handle 39 is pinned. This shaft extends through the extending partition or wall 40 supported on the base 25 by means of the bracket 41. Surrounding the shaft 38 is a bushing 42 furnishing a larger surface in the wall 40, and the shaft is pinned to this bushing. The shaft 38 also carries a group of cams which together with the 55 operating levers provide the coin mechanism.

There are four compartments in the drum 26, and a quarter of a revolution of the drum therefore always brings the new compartment before the chute 73 at which point the bottom opens so 60 that the material falls down into it. At the lower end of the chute 73 there is provided a cover 74. This cover 74 is hinged in the plate 75 by means of the supporting hinge or pivot 76 balanced by means of the weight 77 at the rear end. The hinge 76 as indicated may merely be a slot in the plate 75 with an upper portion 78 and a lower portion 79 bent in reverse directions so as to abut or face the plate 75 on the opposite sides thereof. A handle 80 may be provided to indi-

cate where the individual should press to lower the cover 74 so that the goods may be removed.

The device is particularly adaptable for bulk vending and when filled with peanuts or the like, this in the first place will fill the compartments 5 29 in the drum when the compartments come under the containing chambers. As the drum is rotated to bring the full compartment away from this position, the gates 19 will be dragged across the compartments thus smoothing off the 10 goods, levelling and allowing the drum to be moved or rotated without danger of any sticking. It will also be impossible as quite clearly indicated in the Figures 4 and 5 upon slight consideration for the goods to escape from the compartments, for as the drum is rotated, the compartment or chamber where the goods are contained is always closed off by the goods themselves and by the cylindrical drum. Therefore the device will always maintain its clean condition 15 20 and no goods will be within the frame outside of the compartment. The lever 24, aids, it will be noted in avoiding any sticking as the goods are being delivered to the chute, since it presses downwards and so discharges the goods in the 25 compartments of the drum. If there is any tendency for the goods to stick and not fall out, the lever 24 will operate to cause the goods to fall out practically immediately.

It will be understood that the various details 30 described above may be modified within reasonable details without departing materially from the invention as described, it being understood, however, that the invention is to apply more specifically in the construction and arrangement 35 described in the present application, and therefore, I claim:

1. In a vending machine of the type described, a vertical containing chamber having a sloped wall at the base thereof, a cover formed at the 40 bottom of said chamber, said cover being provided with a circular opening, a partition extending from the sloped wall of said chamber extending diametrically into said opening, said partition being provided at the sides with gates, 45 one gate being tensioned to move in one direction, the other gate being formed of independent elements, each tension to move in a direction opposite from that of the first gate.

2. In a vending machine of the type described 50 a vertical containing chamber having a circular opening at its lower end, a partition positioned at the lower end of said chamber with a sloping side and a vertical member extending from above said opening into the same diametrically across 55 said opening, said vertical member comprising a central rigid portion and two gates at the side thereof, spring means applied to said gates to allow one to swing in one direction and one in the other direction.

3. In a vending machine of the type described, a vertical containing chamber having a circular opening at its lower end, a rotary trap chamber positioned directly below said opening, partition means extending upwards from a diameter of 60 said opening and at an inclination thereto cutting off the other half of said opening, said partition means having its lower edge in line with the lower end of the said opening and comprising a central rigid portion and side pivoted gates, 65 means permitting the swing and return of said gates, one in one direction and the other in the other direction.
